UNITED STATES PATENT OFFICE

2,532,343

HYDRAULIC CONTROL VALVE

Joseph J. Sloemer, Chicago, Ill., assignor to Goodman Manufacturing Company, Chicago, Ill., a corporation of Illinois

Application February 5, 1947, Serial No. 726,644

5 Claims. (CL 277—11)

1

This invention relates to improvements in hydraulic control valves of the type adapted to control operation of a number of hydraulic work-performing devices from a single control handle.

In the operation of certain types of devices such as self-retrieving trolley poles particularly adapted for use on locomotives operable in mines underground, as shown in my companion application Serial No. 726,645, filed herewith and now abandoned, it is necessary to operate the valve to supply fluid to retrieve the trolley pole the instant the pole leaves the wire, to prevent the pole from hitting the mine roof and breaking, and to then swing the pole from side to side by operation of the same valve handle, without removing the hand from the valve handle as the valve handle is also operated to raise the pole, so the operator of the locomotive may replace the pole without leaving his cab and many times without stopping the locomotive.

The principal objects of my present invention are to provide a novel and efficient form of fluid control valve of a type which is particularly adapted to supply fluid under pressure to a self-retrieving trolley pole, which valve is operable by a simple downward movement of the valve handle, to cause the pole to instantaneously drop to the deck of the locomotive, and is also operable to supply fluid under pressure to turn the pole from side to side so the pole may be replaced as the valve is also operated to raise the pole upwardly to engage its current collector with the trolley wire, by a simple sidewise movement of the valve handle in the direction it is desired to turn the pole.

A more specific object of my invention is to provide a novel and efficient form and arrangement of valves in a single valve chamber including a rectilinearly movable piston valve and a valve rotor slidably connected with the piston valve to permit operation of the piston valve by rectilinear movement thereof, and to operate the rotor by pivotal movement of the piston valve about its longitudinal axis, and having fluid passageways so arranged that a single control handle will operate either valve independently of the other and will operate both valves together.

These and other objects of my invention will appear from time to time as the following specification proceeds and with reference to the accompanying drawings wherein:

Figure 1 is a plan view of a valve constructed in accordance with my invention, with certain parts of the operating handle therefor shown in substantially horizontal section;

2

Figure 2 is an end view of the valve shown in Figure 1;

Figure 3 is a sectional view taken substantially along line 3—3 of Figure 1;

5 Figure 4 is a sectional view taken substantially along line 4—4 of Figure 1 and showing the piston valve in a different operative position than in Figure 3;

10 Figure 5 is a sectional view taken substantially along line 5—5 of Figure 1 and showing the piston valve in a still different operative position than in Figures 3 and 4;

15 Figure 6 is a sectional view taken substantially along line 6—6 of Figure 2, showing the valve rotor in one operating position;

Figure 7 is a sectional view taken substantially along the same lines as Figure 6; but showing the valve in a different operating position than in Figure 6;

20 Figure 8 is a sectional view taken substantially along line 8—8 of Figure 2 and showing the valve rotor in a neutral position; and

Figure 9 is a fluid diagram illustrating a preferred form in which the valve of my invention 25 may be used.

Referring now to the drawings, the embodiment of my invention illustrated therein includes a valve casing 10 having a valve chamber 11 extending longitudinally therewith and having a rectilinearly movable piston valve 12 and an aligned pivotally movable valve rotor 13, operable by movement of said piston valve about its longitudinal axis, mounted therein.

The valve casing 10 is herein shown as being of 35 a sectional construction including a body 15 having a part 16 abutting the bottom thereof. Said part 16 has a cylindrical inner wall open at both ends, which forms a continuation of the chamber 11 and has the valve rotor 13 rotatably mounted 40 therein. An end closure member 17 abuts the lower end of said part 16 and closes one end of the chamber 11, and is secured to said part 16 and to said body by means of machine screws 19, 19 extending through said end closure member and 45 part 16 and threaded within said body.

An end plate 20 is secured to the end of the body 15 opposite from the closure member 17, as by machine screws 21, 21. Said member is drilled along its center in alignment with the chamber 50 11, to allow a stem 22 of the piston valve 12 to extend therethrough and outwardly from said valve casing. Packing indicated generally by reference character 23 is provided to prevent the leakage of fluid past said plate 20. Cap screws 28, 28 are 55 provided to secure said turret to said ring.

The turret 25 forms a mounting for an operating handle 29 for the valves 12 and 13. As herein shown, an ear 30 projects upwardly from one side of said turret and has a plurality of links 31, 31 abutting opposite sides thereof and pivotally connected thereto by a pivotal pin 33. Said links are pivotally connected to one end of the operating handle 29 by a pivotal pin 34. Said operating handle extends along opposite sides of a clevis-like member 35 threaded on the upper end of the valve stem 22 and held in fixed relation with respect thereto as by a jam nut 36, so said handle may pivotally move the piston valve 12 about its longitudinal axis. A pivotal pin 37 pivotally connects said operating handle to said clevis-like member, to rectilinearly move said piston valve upon movement of said handle about the axis of the pin 34.

An index is provided to index the piston valve 12 in its various operative positions, which as herein shown includes two parallel spaced upright guide members 38, 39 extending upwardly from said turret 25 and slidably engaging bosses 40, 40 projecting laterally from opposite sides of said handle. Said guide members each have a plurality of spaced apart drilled holes 41, 41 aligned with the corresponding holes on each guide member and corresponding to the positions of said control handle when the piston valve 12 is in a central neutral position, an upper pressure position, or in a lower release position. Said bosses are transversely drilled and have a compression spring 43 mounted therein with balls 44, 44 abutting opposite ends of said spring. Said balls yieldably engaged with the holes 41, 41 by the spring 43, form a spring pressed detent for indexing said handle. A lug 45 projects laterally from said handle in one direction and is engageable with spaced stops 46, 46 projecting from one guide member 39, to limit vertical movement of said handle. The plate 29 is radially drilled to receive a spring 47 and a ball 48 of a ball type index or detent. Said ball is engageable with any one of a plurality of apertures 49, 49 formed in the periphery of the ring 26, to index the various operative positions of the valve rotor 13, as said handle is turned about the longitudinal axis of the piston valve 12, to operate said rotor.

The piston valve 12 is provided with two spaced lands 50, 51 slidably engaging the inside of the valve chamber 11 and spaced on opposite sides of a pressure passageway 53, when said piston valve is in the extreme upper position shown in Figure 3 and is in position to release pressure from the hydraulic operating devices connected thereto. Said pressure passageway leads into said chamber from the outside of the body 15 of the valve casing, for supplying fluid under pressure to said piston valve and to said valve rotor. Said piston valve also has a stem 54 of an irregular formation extending from the land 51 and herein shown as being of a rectangular form in cross section. Said rectangular stem has slidable engagement with a corresponding hole extending through the valve rotor 13, for turning said valve rotor upon turning movement of the handle 29 about the longitudinal axis of said piston valve, either while said handle is operating said piston valve or while said piston valve is in a fixed operative position. A spring 55 is mounted in the closure member 17 and rectangular aperture of the valve rotor 13, for engagement with the end of said valve stem 54, to tend to move said valve towards a neutral position from a pressure posi-

tion, when the hand is removed from the operating handle 29.

A pressure passageway 55 leads from the valve chamber 11 and is blocked by the land 51 of the piston valve 12 when said piston valve is in the intermediate position shown in Figure 5. Said pressure passageway is provided to supply fluid under pressure to a hydraulic operating device such as a retrieving cylinder and piston 52 of a self-retrieving trolley pole, as shown in Figure 9. Said passageway is opened to supply fluid under pressure to said device when said piston valve and the valve handle 29 are in an extreme downward position (see Figure 4). When said valve handle is in the central position shown in Figure 5, fluid under pressure will be held in the device to be operated, and when it is in the extreme upper position shown in Figure 2, fluid pressure will be released from the cylinder 52 through the passageway 55, the central portion of the valve chamber 11 beneath the land 51, and out of the valve to the return through a return passageway 58 (see Figure 4). A drain passageway 56 is also formed in the body 15 and leads from said valve chamber beneath the land 51, and is connected with the part 16 to take care of fluid leaking by the rotor 13 and the devices operated thereby. Said drain also serves as a return passageway to release pressure from one side of said rotor, when said rotor is in the proper operative position.

The pressure passageway 53 is connected by a branch passageway extending along the body 15 parallel to the pivotal axis of the piston valve 12, to a pressure passageway 57 formed in the part 16 (see Figure 3). Said pressure passageway 57 leads into the chamber formed by the inside of said part 16 and is adapted to register with a passageway 59 formed in the valve rotor 13, when said valve rotor is in the position shown in Figure 6. Said passageway 59 leads into and out of said rotor and is herein shown as being of a substantially V-shaped formation in horizontal section. When the valve is in the position shown in Figure 6, said passageway 59 also registers with a passageway 61 formed in said part 16 and leading therefrom, for supplying fluid under pressure through said passageway and to a hydraulic operating device, which may be a rotor 62 of a self-retrieving trolley pole, for turning said rotor and the trolley pole connected therewith (not shown) in one direction (see Figure 9).

A passageway 64 similar to the passageway 59 is formed in the opposite side of the valve rotor 13 from said passageway 59. Said passageway 64 is connected with a return passageway 65 when said valve rotor is positioned as in Figure 6, to relieve pressure from said passageway 64 and to return any fluid which may leak past said rotor. Said return passageway 65 registers with a passageway 66 leading through the body 15 of said valve and opening into the valve chamber 11, for returning fluid through the return passageway 58 to a fluid storage tank 74 through a return pipe 81 (see Figure 9).

The passageway 64 also connects the pressure passageway 57 with a pressure passageway 67 leading from said valve, to supply fluid under pressure to the opposite side of the rotor 62 from the passageway 61, and turn the trolley pole in a reverse direction from which it is turned when fluid is supplied to said rotor from the passageway 61, when the valve is in the position shown in Figure 7. When said valve is in this position,

the passageway 59 is connected to a passageway 68 formed in said part 16, which is connected to the return through the drain passageway 60. Said drain passageway besides serving as a drain, also serves to release fluid from one side of the rotor 62 and to return it to the tank 74 through a pipe 82 connected with the return pipe 81.

Passageways 68 and 70 are provided in said valve rotor and extend therealong in the direction of the axis of said rotor on opposite sides of the axis of rotation thereof and intersect a diametral line extending through the pivotal axis of said rotor. When the valve rotor 13 is in the neutral position shown in Figures 3 and 8, the pressure passageway 57 will register with the passageway 69, to supply fluid under pressure to the valve rotor 13. From thence fluid will pass downwardly along said passageway 69 and along a groove 71 formed in the periphery of said rotor, to and through the passageway 70, to exert a balanced pressure on said valve rotor when said rotor is in a neutral position. Fluid will also be conducted from the passageway 69 through the passageway 70, or from the passageway 69 through the passageway 68, to release fluid from said passageways 61 or 67 when said valve rotor is in the desired operative position.

In Figure 9 a pump 73 is shown as taking fluid from the storage tank 74 and as supplying fluid under pressure to an accumulator 75 through a pipe 76. A check valve 77 is provided in the pipe 76, to prevent fluid under pressure to said accumulator from flowing back to said pump. The pipe 76 is also connected to the pressure passageway 53 of the valve for supplying fluid under pressure thereto. A pipe 78 connects the pressure passageway 55 with the retrieving cylinder 52, to supply fluid under pressure thereto to lower the trolley pole as in my companion application Serial No. 726,645. A pipe 79 connects the pressure passageway 61 with one side of the rotor 62, for supplying fluid under pressure to turn said rotor and the trolley pole connected therewith in one direction. A pipe 80 connects the passageway 61 with the opposite side of said rotor to turn said rotor and the trolley pole connected therewith in an opposite direction. The return pipe 81 connects the passageway 58 of said valve with the fluid storage tank 74, and a return pipe 82 connects the drain passageway 60 with said return pipe 81 and with said fluid storage tank.

Thus when the valve rotor 13 is in the position shown in Figure 6, fluid under pressure will be supplied through the pressure passageway 61 to the valve rotor 62, to turn said rotor in one direction, and fluid under pressure will be released from the passageway 67 through the passageways 69 and 70 communicating with the passageway 68, and out of the valve block through the drain passageway 60. When said valve rotor is in this position or during movement of said valve rotor into or out of this position, the piston valve 12 may be operated to raise or lower the trolley pole at will. When said valve rotor is in the position shown in Figure 7, fluid under pressure may be supplied through the pressure passageway 67 and may be released from the passageway 61 through the passageways 70 and 69 communicating with the return passageways 65 and 66 and 58. Said piston valve may also be operated when said valve rotor is in this position or is moving into or out of this position. When the valve rotor is in the position shown in Figure 8, pressure entering said said rotor through the passageway 69 serves to balance said rotor, to permit ready operation

thereof in either direction, and fluid is released from both sides of the rotor 62 through the passageways 59 and 64, to permit free turning movement of the trolley pole during operation of the locomotive, as shown and described in my companion application Serial No. 726,645.

The pressure and relief passageways of the valve are thus so arranged that fluid under pressure is supplied to the valve rotor 13 when the piston valve 12 is in its various operative positions, so said valve rotor may be operated independently of said piston valve or may be operated upon operation of said piston valve by turning movement of said piston valve about its longitudinal axis, thus providing a simplified form of valve operable to operate a plurality of operating devices from a single control handle either independently or simultaneously of each other.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a hydraulic control valve, a casing having a valve chamber extending therealong, a piston valve rectilinearly movable along said valve chamber, a valve rotor within said valve chamber and spaced from said piston valve, said piston valve including a valve rod having a plurality of pistons thereon and said valve rod having an irregular portion having slidable engagement with said valve rotor for turning said rotor upon turning movement of said piston valve when said piston valve is in its various operative positions, and said valve casing having pressure and relief passageways leading into and out of said valve chamber and arranged to supply or release fluid from either of said valves when the other is in an operative or a neutral position.

2. In a hydraulic control valve, a casing having a valve chamber extending therealong, a piston valve rectilinearly movable along said valve chamber, a valve rotor within said valve chamber and spaced from said piston valve, said piston valve including a valve rod having a plurality of pistons thereon and said valve rod having an irregular portion having slidable engagement with said valve rotor for turning said rotor upon turning movement of said piston valve when said piston valve is in its various operative positions, said casing having pressure and relief passageways leading into and out of said valve chamber and arranged to supply or release fluid from either of said valves when the other is in an operative or neutral position, and a single control handle having operative connection with said valve rod for rectilinearly moving said piston valve along said valve chamber and for turning said valve rod about its longitudinal axis to operate said valve rotor independently of or simultaneously with said piston valve.

3. In a hydraulic control valve, a casing having a valve chamber therein, a piston valve rectilinearly movable along said valve chamber and including a valve rod having a plurality of pistons thereon, a valve rotor mounted within said valve chamber, a slid operative connection between said piston valve and said valve rotor, for turning said rotor upon turning movement of said piston valve when said piston valve is in

its several operative positions or is moving from one operative position to another, and an operating handle having operative connection with said valve rod, said handle being mounted for pivotal movement about the longitudinal axis of said piston valve for turning said piston valve and said rotor to its several operative positions and being pivotally movable about an axis transverse to the longitudinal axis of said piston valve, for moving said piston valve along said valve chamber into its several operative positions.

4. In a hydraulic control valve, a casing having a valve chamber therein, a piston valve rectilinearly movable along said valve chamber, a valve rotor mounted within said valve chamber, 15 said piston valve including a valve rod having a plurality of pistons thereon and said valve rod extending from said pistons into slidable engagement with said rotor for turning said rotor within said chamber upon turning movement of said valve rod about its axis, a pressure passageway leading into said valve casing and chamber for supplying fluid under pressure to said piston valve, another pressure passageway leading from said pressure passageway to said valve rotor for supplying fluid under pressure thereto, a pressure passageway leading from said valve chamber for supplying fluid under pressure to a hydraulic operating device upon rectilinear movement of said piston valve to one position, and another pressure passageway leading from said valve chamber for supplying fluid under pressure to another hydraulic operating device upon pivotal movement of said rotor into one position, said passageways in said casing being so arranged that said piston valve may be operated to supply fluid under pressure to its hydraulic operative device when said valve rotor is in any operative position or is moving into any operative position and said valve rotor may be operated to supply fluid under pressure to its operating device when said piston valve is in any operative position or is moving into any operative position.

5. In a hydraulic control valve, a casing having a valve chamber therein, a piston valve rectilinearly movable along said valve chamber, a valve rotor mounted within said valve chamber, said piston valve including a valve rod having a plurality of pistons thereon, a slidable operative connection between said piston valve and said valve rotor, for turning said rotor upon turn-

ing movement of said piston valve and permitting operation of said piston valve upon turning movement of said rotor, and an operating handle having operative connection with said valve rod, said handle being mounted for pivotal movement about the axis of said piston valve for turning said rotor to its several desired positions by turning movement of said piston valve and being pivotally movable about an axis extending transversely to the axis of said piston valve, for moving said piston valve along said valve chamber into its several operative positions, a pressure passageway leading into said valve casing and chamber, for supplying fluid under pressure to said piston valve, another pressure passageway leading from said pressure passageway to said valve rotor, to supply fluid under pressure thereto, a pressure passageway leading from said valve chamber adjacent said piston valve, for supplying fluid under pressure to a hydraulic operating device when said piston valve is moved into one operative position, a pressure passageway leading from said valve chamber adjacent said rotor for supplying fluid under pressure to another hydraulic operating device when said rotor is moved into one operative position, return passageways leading from said chamber adjacent said piston valve and said valve rotor and connected to a common fluid outlet leading from said casing, said pressure and return passageways being so arranged that said piston valve may be operated by said handle to supply fluid under pressure to or to release fluid pressure from a hydraulic operating device when said valve rotor is in any operative position or is moving into any operative position and said valve rotor may be operated by said handle to supply fluid under pressure to or release fluid pressure from a hydraulic operating device when said piston valve is in any operative position or is moving into any operative position.
